Application September 4, 1936, Serial No. 99,379

6 Claims. (Cl. 113—38)

This invention relates to improvements in presses of the double action type, particularly adapted, though not necessarily limited in its use, for drawing sheet metal or imparting to the article constructed therefrom the desired shape or contour.

A further object is to provide an improved press of the toggle action type in which the dies as would be used in the ordinary type of toggle press, may be used in inverted position, so that the finished stamping or product may be pushed off of the lower die.

15 A further object is to provide an improved press of this character in which only short strokes of both the upper and lower blank holder slides will be required, and in which the upper and lower slides move in opposite directions, with the result that with presses of this character, the objectionable necessity for the slides to move a distance more than twice the depth of the article heretofore drawn or shaped, will be overcome, and the slides will move only a comparatively short distance with respect to the depth of the article, before the latter can be removed from the press.

25 With a press constructed in accordance with the principles of this invention, it will be apparent that a much lower ceiling height will be required for installation, thereby enabling the user to carry materials on the crane over the press crown instead of necessitating their movement by the crane through the aisles.

35 A further object is to provide an improved
press of this character in which the actuating
mechanism for both the slides is disposed in a
hollow crown below the bed, and all of the ro-
tating members as well as the toggle mechanisms
and connecting links will operate in oil or a lubri-
cant, with the attendant advantage that all of the
40 actuating parts will be readily accessible and
will obviate the necessity of the repairman climb-
ing to the top of the press to gain access to such
parts.

45 A further object is to provide an improved
press of this character in which the crown of the
press will be relieved of carrying the loads which
in an ordinary form of toggle press the crown
usually has to take, and will eliminate the diffi-
culties of taking the load on the tie rods, such
50 loads in the present invention being carried by
the connecting links which reciprocate the upper
slide, and due to the fact that such links are of a
substantial size the difficulty of and objectionable
deflection will be overcome.

55 To the attainment of these ends and the ac-

complishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a view partly in vertical section, partly in elevation, and partly broken away of a press of this character constructed in accordance with the principles of this invention and showing the die carrying slides in the position they would assume just at the completion of the drawing or forming operation on the material. 10

Figure 2 is a view similar to Figure 1, showing the die carrying slides separated.

Figure 3 is a vertical, transverse, sectional view taken on line 3—3, Figure 1.

Figure 4 is a detail, vertical sectional view taken on line 4-4, Figure 1. 20

Figure 5 is a detail, vertical sectional view, with parts omitted and as taken on line 5—5, Figure 3. Figure 6 is a view similar to Figure 5, with the parts shown in different positions.

Referring more particularly to the drawings, 25 the numeral 10 designates a bed plate which rests upon the bed 11 of the press, and the bed forms an integral part of a hollow lower crown designated generally by the reference numeral 12.

Supported by the bed of the press and secured thereto in any suitable manner are uprights 13, and connecting the uprights at the upper ends thereof, is a beam or member 14 constituting with the uprights 13 a hollow crown which also constitute an integral structure, and these parts are preferably constructed of comparatively thin sheet material welded or otherwise secured together in an integral structure.

Supported by the bed plate 10 is a work holder 15, which latter encompasses an opening 16 in the bed plate and through which opening 16 the lower die, to be hereinafter described, is adapted to reciprocate.

Arranged to extend across the lower crown 12, and journaled in suitable bearings 11, are a pair 45 of shafts 18, and mounted upon the shafts 18 within the crown and secured for rotation therewith are gears 19, and secured also to the gears 19 for rotation therewith are eccentrics 20, with which eccentric straps 21 cooperate. Extending 50 from the straps 21 are arms 22, which latter are pivotally connected as at 23 to members 24, that in turn are secured to a reciprocating slide 25. This slide 25 supports the lower die 26, which latter is preferably a male die, and the slide 25 55

is reciprocable in a guideway 27 within the hollow base of the press.

The work holder 15 is preferably yieldingly supported by the slide 25 and to that end there may be carried by the slide any suitable number of fluid pressure devices, each comprising a cylinder 26^a of any suitable size and desired configuration.

The cylinders may be attached to the slide or 10 may be formed in the slide as an integral part thereof. In each of the cylinders is a piston 26^b and a piston rod 26^c extends from the piston and is connected to the work holder 15, fluid pressure being admitted into and delivered from the cylinders through a controlling valve 26^d. The fluid pressure is supplied from a line or tank (not shown) but in a way usual with devices of this character. The fluid pressure acts upon the pistons 26^b in such a manner as to normally 20 hold the work holder 15 spaced above the bed 10 (as shown more clearly in Figure 2).

Any number of these eccentrics and eccentric strap connections between the lower slide 25 and the shafts 18 may be provided, according to the 25 length of the press.

The eccentrics 20 are rotated from a shaft 28 through the medium of gears 29 secured thereto for rotation therewith, and these gears 29 respectively mesh with the gears 19, the shaft 28 30 extending through the hollow base and being journaled in suitable bearings 30.

Motion is transmitted to the shaft 28 from a motor 31, the drive shaft of which may be provided with a pulley over which an endless flexible 35 driving member 32 passes, and this belt also passes over one of the elements 33 of a clutch device. This clutch device may be of any desired or suitable construction, but preferably embodies a rotatable member continuously driven by 40 means of the belt 32.

A gear 34 is connected to the member 35 of the clutch device and which latter member may be controlled in any desired or suitable manner, either hydraulically, pneumatically, electrically 45 or otherwise, so as to render the clutch device active to impart rotation to the pinion gear 34, the clutch being under the control of the operator in any suitable manner, not shown. The gear 34 meshes with a gear 36, which latter is 50 secured to the shaft 28 for rotation therewith.

It will therefore be manifest that when the clutch device is rendered active, motion will be imparted to the shaft 28, and this will in turn reciprocate the lower slide 25.

Arranged above the bed of the press, is a slide 55 37 which is arranged to operate within the upper crown, and secured to the slide 37 is a die 38 of any desired contour to conform to and cooperate with the die 26 on the lower slide.

The upper slide is reciprocable toward and 60 away from the bed and is supported by means of bars or rods preferably comprising sections 39-40 adjustably secured together in any suitable manner preferably by means of threads 41 65 on the lower end of the section 39, which telescopes into the section 40 and engaging a threaded nut or collar 42 carried by the section 40. The section 39 is secured to the slide 37 in any suitable manner preferably by passing therethrough 70 and on which rod are arranged nuts or collars 43-44 on opposite sides of the slide.

One end of each of these rods reciprocates through a suitable bearing 45, and the bearings are of such length as to resist lateral strain on 75 the rods.

Within the hollow base or lower crown and adjacent opposite walls 46 but spaced therefrom are partitions 47, forming chambers of any desired size and within these chambers is arranged the operating toggle mechanisms for the upper 5 slide, and suitable braces or ribs 48 are provided for reinforcing the partitions. Extending across the chambers formed by the partitions with the respective walls of the base are stub shafts 49 about each of which a member 50 provided with 10 an arm 50^a is oscillatable. A link 51 is pivotally connected as at 52 by one end to the arm 50^a, and the other end of the link 51 is pivotally connected as at 53 with the lower end of the section 40 of the rod which supports the upper slide 37, 15 preferably by means of the lower end of the section 40 being bifurcated as at 54 to receive the end of the link 51, as shown more clearly in Figure 4.

A second stub shaft 55 is journaled in suitable 20 bearings 56 in the partition 47 and one of the walls 46 of the base (see Figure 4), and pivotally mounted upon the shaft 55 and by one end is a link 57. Another link 58 is pivotally connected as at 59 with the link 57, and the link 58 is pivotally connected at its other end as at 60 with an arm 60^a connected to the member 50, and which arm 60^a is offset with respect to the arm 50^a.

Extending across the hollow base crown and 30 journaled in suitable bearings is a shaft 61, and to this shaft are secured eccentrics 62, the eccentrics being opposed to each other, that is extending on opposite sides of the shaft.

An eccentric strap 63 cooperates with each of 35 the eccentrics 62 and each strap is provided with an arm 64, each of which arms is pivotally connected as at 65 with one of the links 57, so that when the shaft 61 is rotated and the eccentrics 62 rotated, the eccentric straps 63 and arms 64 40 will rock the link 57 about its pivot 55 to cause the parts to move from the position shown in Figure 1 to the position shown in Figure 2, or vice versa. The oscillation of the member 57 about its pivot 55 will cause the member 50 to 45 rock about its pivot 49 to cause a reciprocation of the upper slide 37 through the medium of the bars or rods 39-40.

The shaft 61 is rotated through the medium of gears 66, with which pinion gears 67 mesh, 50 and which gears 67 are secured to the shaft 28 for rotation therewith.

Thus it will be seen that when the shaft 28 is rotated, motion will be imparted through the pinions 29 to the gears 19, which in turn rotate 55 the shafts 18 to reciprocate the lower slide 25, and at the same time the gears 67 carried by the shaft 28 meshing with the gears 66 secured to and rotating with the shaft 61, will rotate the eccentrics 62. This motion of the eccentrics 62 60 through the medium of the eccentric straps 63 and arms 64 will operate or rock the toggle or link mechanism or connection between the eccentric arms 64 and the rods 39-40 to reciprocate the upper slide 37.

It is of course to be understood that the slides 25 and 37 are so arranged and the actuating mechanisms therefor are also so arranged that the slides will operate in timed relation with respect to each other.

Within the die 38 is arranged an ejector 68 70 for ejecting the work 69 from the die 38, and as the lower die 26 recedes or is lowered, the work 69 will be stripped from the lower die.

The ejector 68 may be operated in any desired 75

or suitable manner, either by fluid or hydraulic pressure, and to that end there may be provided cylinders 70 which are carried by the upper slide, and in which cylinder suitable pistons are arranged, the pistons being connected by suitable piston rods 11 with the ejector 68. Fluid pressure being supplied to the cylinder 70 from any suitable source through pipes 72 and controlled in any suitable manner (not shown).

10 The toggle mechanism for actuating the upper slide 37 is so constructed as to produce the desired dwell in the movement of the upper slide and by reason of the fact that the slides move in opposite directions, the long strokes heretofore necessary in toggle presses for the blank holder to rise with respect to the depth of the work to permit of the extraction of the work, has been avoided and the present construction permits of short strokes on both the 20 upper and lower blank holding slides.

The normal position of the lower slide is down so that the upper face of the die 26 will be below the upper face of the work holder 15, so that when the work is placed in the press it will rest 25 upon and be supported by the work holder 15. The outer upper die 38 is lowered until it contacts the work resting upon the work holder 15, which latter cooperates with the die 38 to grip the work and hold it from wrinkling but permitting the material to flow. A further lowering of the die 38 will depress the work holder against the pressure of the fluid in the cylinders 26^a. When the die 38 reaches the limit of its downward movement or as it approaches such 35 limit, the lower slide 25 and die 26 ascend to operate upon the work and during such ascending movement the pistons 26^b will remain stationary, while the cylinders 26^a ascend with the slide 25, the pressure in the cylinders 26^a flowing back and further from the supply to the cylinders through the controlling valves 26^c, which latter are of any ordinary and well known construction.

40 The installation of a press of this type will necessitate a much lower ceiling height and the material can be carried by the cranes over the tops of the presses, instead of necessitating the carrying and transporting of the material through the aisles.

50 Furthermore, the stresses and strains of the slides operating upon the work will not be borne by the crown of the press or by the tie rods but will be exerted against the connecting links which reciprocate the upper slide, and as they are of 55 a considerable size and durable construction, there will be no difficulty by supporting the load as regards the question of deflection of the parts.

55 While the preferred form of the invention has been herein shown and described, it is to be understood that various changes may be made in the details of construction and in the combination and arrangement of the several parts, within the scope of the claims, without departing from the spirit of this invention.

60 What is claimed as new is:—

1. In a double action press, a combined bed and lower crown, a reciprocable slide, a die carried by said slide and operable through the bed, eccentrics housed within said crown, operative connections between said eccentrics and said slide for reciprocating the latter, a reciprocable slide above the bed, a die carried by the last said slide and cooperating with the first said die, a shaft in said crown, disposed between the said 65 eccentrics and separate therefrom, opposed eccentrics secured to said shaft for rotation therewith, toggle mechanisms in said crown and on opposite sides of the said shaft, operative connections between said toggle mechanisms and the second recited slide, operative connections between the said toggle mechanisms and the respective second recited eccentrics for reciprocating the second recited slide, a source of power, and operative connections between said source of power and all of said eccentrics. 10

2. In a double action press, a combined bed and lower crown, a reciprocable slide below the bed, a die carried by said slide and operable through the bed, eccentrics housed within said crown, operative connections between said eccentrics and said slide for reciprocating the latter, a reciprocable slide above the bed, a die carried by the last said slide and cooperating with the first said die, a shaft in said crown, disposed between the said eccentrics and separate therefrom, opposed eccentrics secured to said shaft for rotation therewith, toggle mechanisms in said crown and on opposite sides of the said shaft, operative connections between said toggle mechanisms and the respective second recited eccentrics for reciprocating the second recited slide, a drive shaft having a constant direction of movement, operative connections between said 20 shaft and all of said eccentrics, and means for controlling the operation of said shaft. 15

3. In a double action press, a combined bed and lower crown, a reciprocable slide below the bed, a die carried by said slide and operable through the bed, eccentrics housed within said crown, operative connections between said eccentrics and said slide for reciprocating the latter, a reciprocable slide above the bed, a die carried by the last said slide and cooperating with the first said die, a shaft in said crown disposed between the said eccentrics and separate therefrom, opposed eccentrics secured to said shaft for rotation therewith, toggle mechanisms in said crown and on opposite sides of the said shaft, operative connections between said toggle mechanisms and the second recited slide, operative connections between the said toggle mechanisms and the respective second recited eccentrics for reciprocating the second recited slide, a drive shaft having a constant direction of movement, operative connections between said 30 shaft and all of said eccentrics, and means for controlling the operation of said shaft. 25

4. In a double action press, a combined bed and lower crown, a reciprocable slide below the bed, a die carried by said slide and operable through the bed, eccentrics housed within said crown, operative connections between said eccentrics and said slide for reciprocating the latter, a reciprocable slide above the bed, a die carried by the last said slide and cooperating with the first said die, a drive shaft in said crown intermediate said eccentrics, gear connections between said shaft and said eccentrics, an additional shaft in said crown intermediate and separate from said eccentrics, 40 constant direction of movement, and gear connections between said drive shaft and each of said eccentrics. 45

5. In a double action press, a combined bed and lower crown, a reciprocable slide below the bed, a die carried by said slide and operable through the bed, eccentrics housed within said crown, operative connections between said eccentrics and said slide for reciprocating the latter, a reciprocable slide above the bed, a die carried by the last said 55 slide and cooperating with the first said die, a drive shaft in said crown intermediate said eccentrics, gear connections between said shaft and said eccentrics, an additional shaft in said crown intermediate and separate from said eccentrics, 60 constant direction of movement, and gear connections between said drive shaft and each of said eccentrics. 65

6. In a double action press, a combined bed and lower crown, a reciprocable slide below the bed, a die carried by said slide and operable through the bed, eccentrics housed within said crown, operative connections between said eccentrics and said slide for reciprocating the latter, a reciprocable slide above the bed, a die carried by the last said slide and cooperating with the first said die, a shaft in said crown, disposed between the said 70 eccentrics and separate therefrom, opposed eccentrics secured to the last said shaft and projecting on opposite sides of the latter, toggle mechanism in said crown on opposite sides of the said additional shaft for actuating the second recited slide, operative connections between the said second recited eccentrics and the respective toggle mechanisms for actuating the latter, gear connections between the said additional shaft and the last recited eccentrics, and a gear connection between the said shafts. 75

5. In a double action press, a combined bed and lower crown, a reciprocable slide below the bed, a die carried by said slide and operable through the bed, eccentrics housed within said crown, operative connections between said eccentrics and said slide for reciprocating the latter, a reciprocable slide above the bed, a die carried by the last said slide and cooperating with the first said die, a drive shaft in said crown intermediate 10 said eccentrics, gear connections between said shaft and said eccentrics, an additional shaft in said crown intermediate and separate from said eccentrics, eccentrics secured to the last said shaft and projecting on opposite sides of the latter, toggle mechanism in said crown on opposite sides of the said additional shaft for actuating the second recited slide, operative connections between the second recited eccentrics and the respective toggle mechanisms for actuating the latter, gear connections between the said additional shaft and the last recited eccentrics, and a gear connection 20 between the said shafts, all of the actuating means for said slides being housed within the said crown.

6. In a double action press, a combined bed and lower crown, a reciprocable slide below the bed, a die carried by said slide and operable through the bed, eccentrics housed within said crown, operative connections between said eccentrics and said slide for reciprocating the latter, a reciprocable slide above the bed, a die carried by the last said slide and cooperating with the first said die, a shaft in said crown, toggle links for actuating the last said slide, said toggle links housed within 10 said crown and disposed on opposite sides of said shaft, operative connections between said shaft and said toggle links, a drive shaft, operative connections between said drive shaft and the first said shaft and between said drive shaft and said eccentrics, said slides operating with comparatively short strokes, with respect to the depth of the product produced, work ejecting means carried by the second recited slide, and means whereby the work ejecting means will be actuated with 15 respect to the last recited slide. 20

RUDOLPH W. GLASNER.
